SHOULDER STRAP SUPPORT

Homer D. Counter, P.O. Box 96,
Stirling City, Calif. 95978

Filed May 25, 1972, Ser. No. 257,067

Term of patent 14 years

Int. Cl. D2—99
U.S. Cl. D2—452

FIG.1.

FIG.2.

FIG.3.

FIG. 1 is a top perspective view of a shoulder strap support showing my new design;

FIG. 2 is a bottom perspective view thereof; and

FIG. 3 is a fragmentary view taken from the right of FIG. 1.

I claim:

The ornamental design for the shoulder strap support, as shown and described.
